UNITED STATES PATENT OFFICE.

HENRY ALLEN AVERY, OTTO PETERMANN, AND EDWIN L. HARMON, OF GROTON,
NEW YORK, ASSIGNEES, BY MESNE ASSIGNMENTS, TO L C SMITH & CORONA TYPE-
WRITERS INC., OF SYRACUSE, NEW YORK, A CORPORATION OF NEW YORK.

TYPEWRITING MACHINE.

Application filed November 13, 1926. Serial No. 148,255.

This invention relates to improvements in typewriting machines, and has for its object to provide simple, efficient and compact means for operating the escapement and ribbon mechanisms of the machine from the keyboard; to provide an efficient and compact arrangement of parts for a low or flat three-quarter strike visible typewriting machine; to provide an improved construction of universal bar and an improved means for supporting and guiding the same; to provide an efficient and compact universal bar mechanism for a three-quarter strike typewriting machine having a shifting platen carriage, and escapement and ribbon mechanism (including feeding, reversing and vibrating devices) shiftable with the carriage; and to provide a type-bar operated universal bar mechanism for actuating the ribbon spool rotating and reversing devices, ribbon vibrating devices, and escapement devices, consisting of a minimum number of parts.

To the foregoing and other ends, which will hereinafter appear, the invention consists in the constructions of devices, combinations of elements, and arrangements of parts pointed out in the claims and more fully hereinafter described.

In the accompanying drawings:

Fig. 1 is a central longitudinal sectional view of a portable typewriting machine, illustrating the preferred embodiment of the invention, the escapement mechanism and universal bar mechanism being shown partly in side elevation; and the parts being shown with the platen carriage shift frame in lower case position;

Fig. 2 a view similar to Fig. 1, but with the shift frame in upper case position;

Fig. 3 a detail perspective view showing parts of the case shift devices detached;

Fig. 4 a detail sectional view showing part of the case shift mechanism;

Fig. 5 a sectional view on the line 5—5 of Fig. 1;

Fig. 6 a fragmentary section on the line 6—6 of Fig. 5;

Fig. 7 a fragmentary section on the line 7—7 of Fig. 5, with the parts in upper case position;

Fig. 8 a section on the line 8—8 of Fig. 5;

Fig. 9 a fragmentary perspective view;

Fig. 10 a detail perspective view of part

of the operating means for the ribbon mechanism; and

Fig. 11 a fragmentary perspective view of the right hand universal bar supporting arm.

The main frame of the machine comprises a front wall 10, a back wall 11, side walls 12, and a transverse partition wall 13 which is located in the rear portion of the main frame with its lower edge above the level of the lower edges of the other frame walls and inclines upward and rearward. A rearwardly inclined type-bar segment 14, having an arcuate recess 15 in its rear face, is held to the front face of wall 13 by screws, as shown, with the usual curved type-bar-pivot wire 16 therein lying in a plane parallel with said wall. The type bar action and main frame are constructed as in the well known Corona Four typewriting machine and as disclosed in the application of A. B. Ely and E. L. Harmon, Serial No. 66,000, filed October 31, 1925. The type bar action comprises a system of type bars 17 fulcrumed on wire 16 and guided in the segment slots to strike on the upper front quarter of a platen 18. The type bars are actuated by key levers 19 fulcrumed at their rear ends on a pivot wire 20 held to a fulcrum plate 21 secured to the rear face of wall 13 by suitable fastening screws. The key levers extend downward behind wall 13 and then forward under said wall to the front part of the main frame and are guided in a comb member 22 held to the main frame. The connection between each key lever and its associated type bar comprises a bell-crank lever 23 fulcrumed in a sub-lever segment 24 and connected with the type bar heel and key lever by links 25 and 26, respectively.

The platen carriage 27 and its shift frame are constructed and arranged as shown in said co-pending application. The shift frame comprises a rearwardly and downwardly inclined carriage bed 28 having rigid downwardly and forwardly extending guiding members 29 adjacent opposite sides of the machine connected by a transverse brace rod 30 adjacent their lower ends. The carriage is mounted on the bed in rearwardly tilted position on suitable antifriction bearings, as shown, to travel transversely of the machine, and supports the platen above and in rear of the type bar pivots. The carriage and bed

overlie the space between frame walls 11 and 13, and the guide members 29 extend down between said walls between cooperating guide members 31 held to the main frame 5 side walls in upwardly and rearwardly inclined position, members 29 and 31 being provided with races 32 and 32^a in which are confined suitable ball bearings, said members and races being so arranged as to guide the 10 platen carriage and shift frame to shift obliquely in a plane parallel with the plane of wall 13 and the plane of the segment.

As in the Corona Four machine, and as shown in said co-pending application, the 15 shift frame is actuated by either of two shift key levers 33 having forked rear ends embracing studs 34 on the forward ends of the side arms 35 of a shift torsion and counterbalancing frame. This latter frame comprises 20 said forwardly and upwardly extending arms 35 and a rock shaft 36 to which said arms are held, said shaft being journaled on the side walls 12 of the main frame between back wall 11 and the lower part of the shift 25 frame. The studs 34 are engaged in rearwardly and downwardly extending slots 37 in guide members 29 of the shift frame. The shift levers 33 are fulcrumed intermediate their ends on transverse pivot screws 38 held 30 to brackets 39 secured to the side walls 12 of the frame, which brackets also support a rest 40 for the heads of the type bars. Downward movement of the shift frame is limited by engagement of stops 41 on guide members 29 35 with adjustable stop screws 42 on brackets 43 held to the main frame side walls. Upward movement of the shift frame is limited by the engagement of adjustable stop screws 44 on members 29 with stops 45 on brackets 43. 40 The foregoing parts are all constructed as shown in said co-pending application and as embodied in said Corona Four machine.

In the modified construction of machine shown in the present application the frame 45 35-36 is arranged to counterbalance the shift frame by connecting lugs 46 on arms 35 with the lower ends of counterbalancing springs 47 which are secured at their upper ends to arms 48 of brackets 43. In addition to the 50 platen carriage and platen, there are mounted on the shift frame carriage-feeding means, ribbon vibrating means (including bichrome shift and stencil control), ribbon feeding means, and ribbon feed reversing means, all 55 operable from the keyboard of the machine. Novel means is provided on the main frame of the machine for actuating the carriage feeding, ribbon vibrating, ribbon feeding, and ribbon reversing means on the shift frame 60 from the keyboard in all case positions of the platen carriage, and comprising provisions for actuating all of said means on the shift frame from the character keys through the medium of a type-bar-actuated universal bar, 65 and for actuating the carriage feeding means

from the space bar independently of actuation of the universal bar and the ribbon vibrating, ribbon feeding and ribbon reversing means.

The arcuate sheet metal universal bar 49 is 70 located between the segment 14 and the partition wall 13 and is supported in a plane parallel with the planes of said wall and segment to vibrate in the recess 15 in the segment in a path substantially perpendicular 75 to the planes of said wall and segment and the rearwardly inclined plane in which the type bar pivot wire 16 in the segment lies. Universal bar 49 is carried at the forward ends 80 of a pair of two-part sheet metal side arms comprising front sections 50 and 51 and rear sections 50^a and 51^a, said side arms extending downward and rearward from the universal bar. The sections 50 and 51 are preferably 85 formed integrally with the universal bar, as shown, and extend through pairs of registering apertures 52 and 53 formed, respectively, in wall 13 and fulcrum plate 21, as shown in Figs. 2 and 5. The front portions of sections 50^a and 51^a are rigidly but detachably clamped 90 to the right hand side faces of the rear portions of sections 50 and 51, in rear of wall 13 and plate 21, by pairs of clamping screws 54 threaded into sections 50 and 51.

Sections 50^a and 51^a of the side arms are 95 preferably both offset laterally inward at the rear ends of sections 50 and 51, as shown, and are provided with longitudinal guiding and supporting slots 50^b and 51^b in their offset rear portions extending perpendicular to the planes of wall 13 and the segment. These slots are open at their rear ends and correspond in width with the diameter of rock shaft 36 which extends therethrough and upon which the side arms are thus slidably 100 supported and guided at their rear ends to reciprocate fore-and-aft of the machine. A transverse bridge or spacer bar 55 formed integrally with section 50^a forward of shaft 36 105 abuts the inner face of section 51^a.

The side arms extend rearwardly and downwardly through the shift frame and the shift torsion and counterbalancing frame, between guide members 29 and rock arms 35, and above brace rod 30 and below the carriage bed 28, to a point adjacent frame wall 11 and the base line of the main frame and are supported and guided intermediate the universal bar and shaft 36 on fore-and-aft rocking supporting arms 56 and 57. Rocker arms 56 115 and 57 are preferably formed of sheet steel and are brazed or welded at their lower ends on the hub portions of a short transverse rock shaft 58 preferably formed of steel and having its reduced hub portions or trunnions 58^a 120 journaled on the inner ends of horizontal bearing screws 59 threaded inward through the rear ends of a pair of arms 21^a and 21^b 125 formed integrally with fulcrum member 21 and extending rearward and downward to a 130

point forward of shift frame rod 30 and close to the base line of the main frame. Bearing screws 59 are adjustable endwise to center rock shaft 58 and its arms 56 and 57 and are held in adjusted position by lock nuts 60. Arms 56 and 57 extend upward and rearwardly forward of shift frame rod 30 at a slightly less angle from the vertical than the wall 13 and shift frame and have pivot holes in their upper ends in which are engaged the reduced inner ends of pivot studs 61, the reduced outer ends of the studs being swaged in apertures in the universal-bar-carrying arm sections 50 and 51, respectively, forward of side arm sections 50^a and 51^a.

Forward movement of the universal bar is limited by engagement of said bar with the front wall of recess 15 in the type bar segment 14, and rearward movement of the universal bar is limited by engagement of an adjustable overthrow preventing stop 62—63 with rock shaft 36. This stop comprises a fore-and-aft bendable integral finger 62 on side arm section 51^a, depending from the top wall of slot 51^b in said section, and having a rubber cushioning sleeve 63 frictionally held thereon. Stop 62—63 is adjusted to engage shaft 36 only after a full printing movement of a type bar, the type bars being provided adjacent to their pivots with lugs 17^a for engaging the front edge of the universal bar and moving it rearward, and being also preferably provided with lugs 17^b for engaging an anvil face 14^a on segment 14.

The universal bar is normally held at the forward limit of its movement by a return spring, hereinafter described, and its extent of throw and the throw of rock arms 56 and 57 are such that the pivot studs 61 swing between points substantially equal distances at opposite sides of a plane through the axis of rock shaft 58 perpendicular to the plane of the carriage bed and parallel with wall 13, as will be apparent from Figs. 1 and 2. The described arrangement and movement of rock arms 56 and 57, together with the arrangement of slots 50^b and 51^b longitudinally of the side arms and perpendicular to the plane of wall 13, provides for supporting and guiding the universal bar 49 to vibrate obliquely to the horizontal plane of the machine in a path substantially perpendicular to the plane of the segment and its type bar pivot wire.

The ribbon vibrating, ribbon feeding, and ribbon reversing means on the shift frame are all operated from a single tappet-carrying rock shaft 64. This rock shaft is preferably formed of steel, extends transversely of the machine above the key levers, and has reduced bearing portions or trunnions 64^a at its ends which are journalled in arms 65^a and 66^a of a pair of sheet metal brackets 65 and 66. The brackets 65 and 66 are detachably held to the front face of the frame wall 13 at opposite ends of the segment 14 by fastening

screws 67, and the arms 65^a and 66^a lie flatwise in vertical planes extending fore-and-aft of the machine and curve downwardly and rearwardly to points closely under the lower edge of wall 13 where they are provided with bearing apertures for the trunnions of shaft 64, which is thus supported closely adjacent and under the edge of wall 13 above the character key levers and below the shift key levers to oscillate about a horizontal axis. A sheet metal rock arm 68 extends downwardly, and preferably slightly forwardly, from rock shaft 64 at a point intermediate the ends of said shaft and substantially in the fore and aft vertical plane of side arm 51—51^a of the universal bar. This rock arm is brazed or welded on shaft 64 and extends down between adjacent key levers of the machine to a point below the key levers and close to the base line of the main frame, and is connected at its lower end with the forward end of a fore-and-aft extending and substantially horizontal rigid wire link 69. The link 69 extends under shaft 58 and is connected at its rear end with the lower end of an arm 70 formed integrally with side arm section 51^a and extending downward and preferably slightly forward from the forward end of said section to a point below rock shaft 58 and between said shaft and the shift frame brace rod 30.

A pair of sheet metal tappet arms 71 are brazed or welded on the trunnions 64^a of shaft 64 and extend forwardly from said shaft and then upwardly and rearwardly directly in front of wall 13, said arms being formed with integral hook-like tappets 72 at their upper ends disposed flatwise in a substantially horizontal plane and having rearwardly facing abutments or contact edges 72^a thereon extending inward transversely of the machine. The universal bar 49 and tappet shaft 64 are preferably both returned or restored to normal position by means common to both thereof. To this end, at least one additional depending rock arm 73 is fixedly held to said shaft. As shown, a single rock arm 73, preferably formed integrally with the left hand tappet arm 71, is provided, said rock arm extending downward below the level of the key levers and having the rear end of a coiled return spring 74 attached to its lower end. Spring 74 extends forward from arm 73 and is connected at its forward end with a sheet metal spring-anchor bar 75. This anchor bar extends transversely of the machine and is supported in slots 76 in arms 43^a of brackets 43, which bracket arms extend forward under frame wall 13 and support bar 75 below the key levers and forward of the upturned rear end portions of said key levers. Return springs 77 for the character key levers are connected at their forward ends to bar 75 and at their rear ends to the key levers, as in the Corona Four machine. A third sheet

metal tappet arm 78 is brazed or welded on rock shaft 64 and lies flatwise in a vertical plane located between the left hand tappet arm 71 and the left hand end of the type bar 5 segment 14. This tappet arm 78 extends upward and forward from shaft 64, and the outer end of a horizontally and transversely extending tappet screw 79 is threaded into the forward end of said arm. It will be obvious 10 that spring 74 will normally hold the universal bar, and the three tappet arms and tappets held to shaft 64, in the positions thereof shown in the drawings.

The particular ribbon spool rotating means 15 and the means for reversing the direction of feed of the ribbon, mounted on the shift frame, are not claimed per se in this application. The novel operating mechanism, for the spool rotating means and the ribbon feed 20 reversing means, disclosed and claimed herein, is particularly adapted for use in connection with the spool rotating and feed reversing means shown, but may be employed to actuate other forms of spool rotating and reversing means. The ribbon feeding and reversing devices shown are constructed and operate, and are supported from the shift frame, as more fully shown and described in the co-pending application of Ely and Har- 25 mon, hereinbefore referred to, and as in the Corona Four machine, and will be only briefly described herein.

The ribbon spools 80 are held to the split or slotted upper ends of hubs 81 of spool rotating ratchet wheels 82 to rotate therewith, said ratchet hubs being journaled on reduced upper portions of vertical posts 83 fixed on a pair of sheet metal brackets 84. The brackets 84 are secured by screws 85 at their 40 rear end to the bottom face of the carriage bed 28 and extend forward over frame wall 13, supporting the spools substantially level with the platen at opposite sides of the system of type bars. The spools are housed in cups 86 attached to the brackets, and the bi-chrome ribbon 87, wound on and attached to the barrels of the spools, passes through openings 88 in the cups across the front of the platen.

50 The ratchets are adapted to be rotated by pawls 89 loosely pivoted intermediate their ends on transversely and horizontally extending pivot screws 90 threaded in ears 91 depending from brackets 84. Springs 100 connecting the pawls (above their pivots) with the brackets, normally tend to tilt the pawls laterally on their pivot screws to pull the upper or nose ends of the pawls outwardly into the toothed edges of the ratchets. Horizontally swinging detent pawls 92 pivoted on the brackets at 93 have their noses normally urged to the toothed edges of the ratchets by springs 94 connecting the said pawls with brackets 84. Cams 95 on the forward arms of horizontally swinging feed re-

versing levers 96 (pivoted on the brackets 84 at 97 and having their rear arms connected by a rigid transversely extending wire link 98) are adapted to disengage and hold disengaged from one ratchet wheel the 70 ratchet-rotating and ratchet-detent pawls associated with said wheel and simultaneously permit action on the other ratchet wheel of the rotating and detent pawls associated therewith. 75

The swinging and tiltable pawls 89 are connected below their pivots, by rigid wire links 99, with the tappet arms 71, said links extending upward and forward from the tappet arms to the pawls in such manner that the forward end of each link swings between points located substantially equal distances below and above a plane through the point of connection of the link with the associated tappet arm perpendicular to the plane of shift of the shift frame, when the shift frame is shifted from one case position to the other, so that the pawls will be given substantially equal swinging movements in both case positions when shaft 64 is oscillated. The arrangement of the pawls and ratchets and the novel operating mechanism therefor is such that the spools are turned in opposite directions by the pawls, and the active or winding spool is rotated by its pawl on the return stroke of the universal bar 49. 90

The interconnected cams 95 for reversing the feed of the ribbon are simultaneously shifted in opposite directions by first one and then the other of the tappets 72 through the medium of a pair of ribbon-controlled connecting devices carried by the cams. Each of these devices comprises an upstanding sheet metal lever 101 pivoted intermediate its ends to swing transversely of the machine 100 on a pivot screw 102 carried by an ear 103 depending from the adjacent cam 95. A weight 104 on each lever 101 normally holds the lever upright against a stop lug 105 on ear 103 with the lower arm of the lever out 105 of the path of movement of the adjacent tappet 72. 110

A wire ribbon guide loop 106 carried by the upper arm of each lever 101 is adapted to be engaged by one of the ordinary reversing abutments or metal eyelets (not shown), carried by the ribbon 87 near its opposite ends, to rock the lever 101 (associated with the spool from which the ribbon has been exhausted) to swing the lower arm of said lever 115 outward into the path of movement of the edge portion 72^a of the adjacent tappet 72. Upon return movement of the tappet (following setting of the connecting lever into active position) the tappet will push rearward 120 on the lower arm of the lever and carry it bodily rearward, thereby rocking the adjacent cam 95 rearward to permit the feed and detent pawl associated with the adjacent ratchet to become effective on the adjacent 125 130

spool to rewind the ribbon thereon, the cam 95 associated with the full spool being at the same time rocked forward to throw out the feed and detent pawls associated therewith 5 and hold them out of effective action on the adjacent ratchet.

A detent device comprising a spring detent 107 held to the right hand bracket 84 at 107^a and cooperating with a finger 108 on right 10 hand lever 96, yieldably holds the cams 95 in their shifted positions. In order that tappets 72 may impart uniform bodily rearward movement to connector levers 101 in both 15 case positions of the obliquely shiftable shift frame, the lower arms of said levers are stepped to provide contact faces 101^a and 101^b adapted to be engaged by tappet edges 72^a in lower and upper case positions, respectively, of the shift frame. The face 101^b is 20 located forward of the face 101^a a distance corresponding with the extent of bodily rearward movement of the lever 101 due to the upward and rearward movement of the shift frame from lower to upper case.

25 The ribbon vibrating means carried by the shift frame is operated by the tappet screw 79 on the tappet arm 78 held to rock shaft 64. This vibrating means is preferably constructed and arranged, and is operated by said tappet, in the manner more fully shown and described in our application for patent, Serial No. 148,254, filed November 13, 1926, but the said tappet may be employed to operate other forms of ribbon vibrating means.

30 A sheet metal bracket 109, held by screws 110 to the bottom face of the carriage bed 28 adjacent the left hand spool bracket 84, extends forwardly over wall 13 and is provided at its front edge with an upstanding 40 arm 111 lying flatwise in a plane parallel with said wall. A ribbon guide supporting and vibrating lever 112 extends transversely of the machine in front of said bracket arm and is pivotally held to said arm intermediate its ends by a pivot screw 113 to rock 45 up and down in a plane parallel with wall 13. A ribbon guide 114 lies behind a type bar guide 115 which is held by screws, as shown, to the front face of wall 13 above the central portion of the segment and extends upward and rearward in front of the platen parallel with said wall. The ribbon 50 87 is adapted to be threaded through said ribbon guide 114, which is constructed, and slidably guided on the type guide 115 by fingers 116 to vibrate in a plane parallel with the path of case shift movement of the platen, as in the Corona Four machine and in said co-pending application of Ely and Harmon, 55 hereinbefore referred to. The inner end of lever 112 lies behind the ribbon guide and is provided with a horizontal slot 117 in which is engaged the shank of a headed stud 118 carried by the ribbon guide.

60 A vibrator 119 for lever 112 extends down-

ward and forward from the outer arm of the lever to the actuating tappet 78 forward of wall 13 and at the left hand side of the segment and the system of type bars pivoted in the segment. The vibrator is 70 reciprocable endwise in a rearwardly inclined path, being movable upward (and normally held elevated) by a supporting and return spring 120 and being movable downward by tappet screw 79 which has a down push connection with a tappet toe 121 pivoted on the vibrator at 121^a to swing fore and aft of the machine.

Spring 120 is connected with bracket 109 and tappet toe 121 in such manner as to 80 normally hold the vibrator 119 elevated and normally hold the toe 121 rocked rearward to maintain an abutment 122 thereon engaged under tappet screw 79. A fore-and-aft swinging cam lever 145 pivoted on bracket 85 109 at 146 has its lower end extended inward behind toe 121 and is adapted to swing toe 121 forward about its pivot at the beginning of an upper case movement of the shift frame to disengage abutment 122 from 90 under tappet screw 79 and permit engagement of a second and lower abutment 123 on the toe under said screw at the end of an upper case movement of the shift frame. Cam lever 145 is rocked forward about its 95 pivot 146 upon a minute lift of the shift frame by a cam shoulder 147 on a supporting finger 148 riding up over a forwardly and upwardly extending lug 149 formed on the left hand bearing bracket 65 for the 100 tappet shaft 64, said lug being normally engaged with the upper end portion of said cam shoulder. Abutments 122 and 123 constitute the lower edges of the branches of an inverted-L-shaped slot in the toe 121, the 105 upper edges of which branches are held out of contact with screw 79 by spring 120.

The vibrator 119 is guided at its lower end on screw 79, having a longitudinal guide slot 124 therein through which the shank of said screw extends and which is so arranged that the ends thereof are not engageable by said screw shank at any time. The vibrator is guided adjacent its upper end by a transversely extending link 125 which is pivoted 110 at 126 on bracket arm 111 and is pivotally held to the vibrator at 127.

A transversely swinging spring steel connector arm 128 is pivoted at 129 on the vibrator and extends upward through a yoke 130 120 formed on the vibrator. This arm is provided at its upper end with a finger piece 131 whereby it may be adjusted transversely by flexing it rearward and swinging it about its pivot 129 to position the shank of a headed stud 132, carried by the arm, in either end portion of a longitudinal slot 133 (formed in the outer arm of lever 112), or in register with a connected slot 134 formed in said lever arm and extending upward from the lower 130 125

edge of the lever to the middle portion of slot 133.

A stop 135 on the vibrator cooperates with a cam edge 136 on yoke 130 to hold the connector with stud 132 in the left hand end of slot 133 for effecting a short throw of the ribbon guide for writing in black. A stop 137 on the vibrator cooperates with a cam edge 138 on yoke 130 to hold the connector with stud 132 in the right hand end of slot 133 for effecting a long throw of the ribbon guide for writing in red. A notch 139 in the yoke is adapted to receive the resilient connector arm 128 to lock the same with stud 132 in line with slot 134 to render the vibrator ineffective on lever 112 for writing stencils. Cooperating stops 140 and 141 on lever 112 and bracket arm 111 limit upward movement of the vibrator and downward movement of the ribbon guide, which guide normally holds the ribbon lowered to uncover the printing point on the upper front quarter of the platen designated by the arrow P. A stop 142 on the vibrator is adapted to engage the upper face of bracket 109 to limit down throw of the vibrator. Cooperating stops 143 and 144 on the lever 112 and bracket arm 111 are adapted to engage only when the device is adjusted for writing in red, these stops being employed to prevent overthrow of the ribbon guide due to momentum acquired during the long throw of the guide in writing in red. The outer arm of lever 112 is guided between fingers 109^a on bracket 109.

It will be obvious that the ribbon guide will be moved upward by tappet 79 on the printing strokes of the type bars to cover the printing point if the connector 128 is adjusted for printing through either half or color zone of the bichrome ribbon, and that the guide will be returned to uncover the printing point by spring 120. It will also be obvious that the guide will remain stationary in lowered position during the type bar strokes when the connector is adjusted to stenciling position. As abutments 122 and 123 on tappet toe 121 are stepped longitudinally of the toe a distance corresponding with the extent of case shift movement of the shift frame, it will be obvious that tappet 79 will depress the vibrator 119 equal distances in both case positions of the shift frame.

The carriage feeding mechanism is also mounted to partake of the case shift movements of the platen carriage. The carriage feeding means shown comprises a rotary escapement constructed and operating as more fully shown and described in our application for patent, Serial No. 148,257, filed November 13, 1926.

As the operating means for the escapement mechanism may be employed to actuate other forms of escapement mechanism,

only so much of the escapement herein shown as is necessary to a clear understanding of the present invention will be described.

A sheet metal bracket 150 held to the bottom face of the carriage bed has depending fore-and-aft extending side arms. A sheet metal dog rocker 152 has depending side ears 153 journalled on horizontal transversely extending pivot screws 154 carried by the rear ends of said bracket arms. The dog rocker carries a fixed dog 155 and a loose dog 156 projecting forwardly therefrom and cooperating with the toothed escapement wheel 157 fixed on the lower end of a shaft 158 journalled in the bracket 150 to rotate about an axis perpendicular to the carriage bed. A pinion 159 fixed on the upper end of shaft 158, which extends through the bed, meshes with a rack 160 secured to the carriage. The carriage is normally urged to the left, as usual, by a spring drum and draw band (not shown) which may be arranged as in the Corona Four machine. A return spring 161, connecting a lug 162 on the right hand pivot ear 153 of the dog rocker with the bracket 150, normally holds the dog rocker in the position shown in the drawings with the fixed dog above the plane of escapement wheel 157 and the loose dog engaged with the wheel. A stop arm 163 extending forward from the left hand pivot ear 153 of the dog rocker normally engages under bracket 150 to limit return movement of the dog rocker.

The left hand pivot ear 153 of the dog rocker is formed with a downwardly and forwardly extending arm 164. This arm extends down outside of the inwardly offset slotted rear portion of side arm section 50^a of the universal bar supporting means and is provided with a lug 165 at its lower end extending outward beyond the rear end of side arm section 50 and lying flatwise in a plane perpendicular to the wall 13 and the path of movement of the shift frame.

A tappet or shoe 166, formed on the rear end of side arm section 50 and projecting rearward beyond the rear end of the outwardly offset forward portion of side arm section 50^a, is adapted to engage the forward edge of lug 165 and push rearwardly and downwardly thereagainst on the printing strokes of the type bars to rock the dog rocker to carry the loose dog down out of co-operative engagement with escapement wheel 157 and the fixed dog into co-operative engagement with the wheel. The rear contact edge of tappet 166 inclines upward and rearward parallel with the plane of shift of the carriage and dog rocker, and it will be obvious that the dog rocker will be rocked uniformly in both case positions of the platen carriage.

It will be evident that whenever a character key is actuated the universal bar 49 will be actuated, and that actuation of the universal bar causes actuation of the escapement

mechanism and the ribbon vibrating and feeding mechanisms, except, of course, that the ribbon guide will remain quiescent when the controller 128 is adjusted for stenciling. It is desirable that the escapement mechanism may be actuated from the space bar without causing an operation of the ribbon mechanism. To this end novel means has been provided for actuating the dog rocker 172 from the space bar without actuating the universal bar or any part of the ribbon mechanism of the machine.

The space bar 167 is supported forward of the character keys on the forward ends of a pair of sheet metal rock arms 168 which are fixed on a transverse rock shaft 169 having trunnions 170 at its ends journalled in forwardly extending ears 171 punched up from the key lever guide comb 22. A rock arm 172 fixed on said shaft extends downward and forward in front of the comb and is pivotally connected at its lower end by a transverse pivot screw 173 with the forward end 20 of a fore-and-aft extending and endwise reciprocal tappet bar 174.

Tappet bar 174 extends rearwardly through a guide slot 175 in comb 22 and under sub-lever segment 24 and the type-bar segment 14, and also under rock shaft 64 and wall 13, and over anchor bar 75. Bar 174 is bent upward behind wall 13 forward of shaft 58 and then extends rearward and downward along the outer side of side arm section 50 of the universal bar supporting means over rod 30. This inclined rear portion of the bar is formed with a guide slot 176 extending substantially perpendicular to wall 13 in which is engaged the reduced shank portion 177 of a horizontal supporting and guiding stud 177 carried by and extending outward from the universal bar supporting and guiding rock arm 56 on rock shaft 58. A tappet or shoe 178, formed on the rear end of bar 174 alongside tappet 166, has its rear contact edge parallel with the path of shift of the platen carriage and dog rocker and arranged to push rearwardly on the contact lug 165 on the dog rocker arm 164.

Bar 174 and the space bar are returned and yieldably held in the position shown in the drawings by a return spring 179 connected at its rear end with the bar 174 and at its forward end with the anchor bar 75. An up-standing stop lug 180 formed on bar 174 engages the rear face of guide comb 22 to limit return movement of the space bar 167 and tappet bar 174. Down throw of the space bar and rearward movement of the tappet bar is limited by stop lugs 181 on the space-bar-supporting arms engaging the upper ends of the two forward rubber supporting feet 182 attached to the main frame, this stop arrangement for limiting the down throw of the space bar being the same as that embodied in the Corona Four machine.

With the described arrangement for operating the dog rocker from the universal bar and space bar, tappet bar 174 (while supported or guided in part on a swinging part of the universal bar supporting and guiding means) is operable without moving the universal bar, and the universal bar is operable without actuating the tappet bar 174. The rock arms 172 and 56 and stud 177 support and guide tappet bar 174 so that its tappet carrying end moves rearward and downward, when the space bar is depressed, with the contact edge of tappet 178 always substantially parallel with wall 13, the pivot 173 moving rearward and downward and slot 176 being inclined rearward and downward. Tappet 166 is preferably arranged slightly forward of tappet 178, which latter tappet preferably normally engages contact lug 165 on the dog rocker, so that the dog rocker may be actuated by a short dip of the space bar, so that the ribbon vibrator will be moved throughout the movement of the universal bar to insure proper action of the vibrator, and so that the dog rocker will be rocked from 90 and will return to normal position, respectively, during a minimum final part of the printing stroke and a minimum initial part of the return stroke of a type bar, thus insuring proper action of the escapement during rapid writing.

It will be observed that the escapement, ribbon vibrating, ribbon feeding and ribbon reversing means, and the means for operating the same, are arranged in a manner permitting the machine to be made low and compact without undue crowding of the parts and without the necessity of making the parts of undesirable small size. The operating mechanism is conveniently accessible and of 100 simple and sturdy construction, consists of a minimum number of parts, and is arranged to permit actuation of the escapement independently of the ribbon from the space bar. The sectional construction of the universal 110 bar and the universal-bar-carrying means, together with the detachable mounting of the segment, provides for a sturdy and accurately guided universal bar and supporting means therefor which may be conveniently 115 assembled in a low three-quarter-strike machine in compact relation with the shift frame. The universal bar supporting and guiding means is simple and compact, and the space bar mechanism consists of a minimum number of parts.

It will be further observed that the escapement mechanism is operable from one side arm of the universal bar and the ribbon mechanism is operable from the other side arm of 125 the universal bar, so that the load on the universal bar supporting means is so distributed as to reduce to a minimum the liability of objectionable canting of the universal bar, and to reduce strain and fric- 130

tional resistance in the universal bar mechanism to a minimum.

It will also be noted that the ribbon operating mechanism on the main frame is compactly arranged with relation to the main frame and the universal bar, the tappet shaft underlying wall 13 and the universal bar, and the tappet arms 72 being located at opposite ends of the universal bar and segment. The 10 ribbon feeding means and ribbon reversing means are compactly arranged forward of the plane of wall 13 and forward of the shift frame, and are supported from the shift frame and both operable from the tappet 15 arms 72. Tappet arms 72 and tappet arm 78 are all held to shaft 64, the ribbon vibrating means being connected with arm 78 and extending up therefrom around one end of the segment to the ribbon guide which is mounted on the type guide. The ribbon vibrating means, including the bichrome shift and stenciling control means, is mounted on the shift frame forward of the plane of wall 13 and is conveniently accessible. The ribbon 20 feeding and reversing devices are also conveniently accessible. The escapement mechanism is shiftable with the carriage and located in rear of the plane of wall 13, and, as before described, is operable from one side 25 arm of the universal bar, while the ribbon mechanism is operable from the other side arm of the universal bar and located forward of the plane of wall 13, thus avoiding objectionable interweaving or crowding of parts of 30 these mechanisms and their operating connections with the universal bar. It will also be noted that the escapement mechanism is located to the rear of the type action and does not extend into the supporting and carrying 35 means for the universal bar.

The escapement mechanism, ribbon vibrating mechanism, ribbon feeding mechanism, and ribbon reversing mechanism are all operated from a single type-bar-actuated universal bar. The ribbon spools are rotated by the feed devices, and the ribbon reversing mechanism (when automatically rendered active) is actuated, on the return stroke of the universal bar, thus contributing to easy 40 action of the machine. The peculiar manner of supporting the universal-bar-carrying means is efficient and contributes to reduction in the number of parts in the machine.

What we claim is:

1. In a typewriting machine, a platen, a platen carriage, key-operated type bars, an arcuate type-bar-actuated universal bar, means for supporting and guiding the universal bar to move rearward when struck by a type bar, said means being located entirely to the rear of the universal bar and including a pair of fore-and-aft extending arms spaced apart transversely of the machine and supporting the universal bar at their forward 60 ends, a rock shaft extending transversely of

the machine under the universal bar, a rock arm depending from said shaft, a pair of rock arms extending upward from said rock shaft at opposite sides of the machine and between which the universal bar is located, ribbon feeding and reversing means operable from said upwardly extending rock arms, ribbon vibrating means, an actuator for said vibrating means held to said rock shaft, escapement mechanism for the carriage, means carried by one of said universal-bar-supporting arms for actuating the escapement mechanism, and means connecting the other universal-bar-supporting arm with said depending rock arm for rocking said shaft. 70

2. In a typewriting machine, a platen, a platen carriage, key-operated type bars, a space bar, an arcuate type-bar-actuated universal bar, vibratory means for supporting and guiding the universal bar to move rearward when struck by a type bar, a rock shaft extending transversely of the machine, a rock arm depending from said shaft, a link connection between said rock arm and said vibratory universal-bar-supporting means, a pair 85 of rock arms extending upward from said rock shaft at opposite sides of the machine, ribbon feeding and reversing means operable from said upwardly extending rock arms, ribbon vibrating means, an actuator for said vibratory means held to said rock shaft, escapement mechanism for the carriage, an actuator for the escapement mechanism carried by said vibratory universal-bar-supporting means and vibrating therewith, and a second actuator for the escapement mechanism operable solely by said space bar and supported and guided on said vibratory universal-bar-supporting means for independent movement between said second actuator and 95 said vibratory means.

3. In a typewriting machine, a platen, a carriage for the platen, a universal bar, a vibratory support for said universal bar, an escapement for the carriage including a dog rocker, an actuator connected to vibrate with said universal bar for actuating the dog rocker, a space bar, a vibratory actuator for the dog rocker operable by the space bar and having a pin-and-slot supporting and guiding connection with said vibratory universal bar support whereby the actuators may vibrate independently, said dog rocker being loosely engaged by both actuators, and key-operated type bars for vibrating the universal bar. 100

4. In a typewriting machine, a platen, means for case-shifting the platen including a rock shaft extending transversely of the machine, an arcuate universal bar, side arms 115 supporting said universal bar at their forward ends and slidably guided at their rear ends on said shaft, and key-operated type bars for vibrating said universal bar. 125

5. In a typewriting machine, a platen, 130

means for case-shifting the platen including a rock shaft extending transversely of the machine, an arcuate universal bar, side arms supporting said universal bar at their forward ends and slidably guided at their rear ends on said shaft, a pair of fore-and-aft swinging rock arms on which said side arms are supported intermediate the rock shaft and universal bar, and key-operated type bars for actuating said universal bar.

6. In a typewriting machine, a platen, means for case-shifting the platen including a rock shaft extending transversely of the machine, an arcuate universal bar, side arms supporting said universal bar at their forward ends and slidably guided at their rear ends on said shaft, a pair of fore-and-aft swinging rock arms on which said side arms are supported intermediate the rock shaft and universal bar, key-operated type bars for actuating said universal bar, and ribbon mechanism and escapement mechanism operable from said universal bar.

7. In a typewriting machine, a platen, means for case-shifting the platen including a rock shaft extending transversely of the machine, an arcuate universal bar, side arms supporting said universal bar at their forward ends and slidably guided at their rear ends on said shaft, a pair of fore-and-aft swinging rock arms on which said side arms are supported intermediate the rock shaft and universal bar, key-operated type bars for actuating said universal bar, escapement mechanism operable from one side arm of said universal bar, and ribbon mechanism operable from the other side arm of said universal bar.

8. In a typewriting machine, a main frame; a platen carriage; a support for the carriage shiftable to change case; ribbon vibrating means, ribbon spool rotating devices, and ribbon reversing devices shiftable with said support; a type bar actuated universal bar; a rock shaft on the main frame; a connection between said rock shaft and universal bar for rocking the shaft; a pair of actuators on said rock shaft for operating the ribbon reversing devices and spool rotating devices in all case positions of the shift frame; and an actuator on said rock shaft for operating the ribbon vibrating means in all case positions of the shift frame.

9. In a typewriting machine, a main frame, a platen carriage, an up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type bars for actuating said universal bar, a pair of transversely spaced arms

carrying said universal bar at their forward ends and having longitudinally extending guide slots at their rear ends through which said rock shaft extends, said universal-bar-carrying arms extending through the shift frame and supported and guided on the rock shaft between the rock arms, and fore-and-aft swinging means mounted on the main frame between the rock shaft and universal bar and pivotally connected with said universal-bar-carrying arms forward of the rock shaft for supporting and guiding said arms.

10. In a typewriting machine, a main frame, a platen carriage, and up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type bars for actuating said universal bar, a pair of transversely spaced arms carrying said universal bar at their forward ends and having longitudinally extending guide slots at their rear ends through which said rock shaft extends, said universal-bar-carrying arms extending through the shift frame and supported and guided on the rock shaft between the rock arms, fore-and-aft swinging means mounted on the main frame between the rock shaft and universal bar and pivotally connected with said universal-bar-carrying arms forward of the rock shaft for supporting and guiding said arms, escapement mechanism for the platen carriage mounted to shift with the shift frame, and an actuator for said escapement mechanism on one of said universal bar-carrying arms.

11. In a typewriting machine, a main frame, a platen carriage, an up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type bars for actuating said universal bar, a pair of transversely spaced arms carrying said universal bar at their forward ends and having longitudinally extending guide slots at their rear ends through which said rock shaft extends, said universal-bar-carrying arms extending through the shift frame and supported and guided on the rock shaft between the rock arms, fore-and-aft swinging means mounted on the main frame between the rock shaft and universal bar and pivotally connected with said universal-bar-carrying arms forward of the rock shaft for supporting and guiding said arms.

said arms, ribbon vibrating means mounted on the shift frame, an actuator for said ribbon vibrating means mounted on the main frame, and an operating connection between said actuator and one of said universal-bar-carrying arms.

12. In a typewriting machine, a main frame, a platen carriage, an up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type-bars for actuating said universal bar, a pair of transversely spaced arms carrying said universal bar at their forward ends and having longitudinally extending guide slots at their rear ends through which said rock shaft extends, said universal-bar-carrying arms extending through the shift frame and supported and guided on the rock shaft between the rock arms, fore-and-aft swinging means mounted on the main frame between the rock shaft and universal bar and pivotally connected with said universal-bar-carrying arms forward of the rock shaft for supporting and guiding said arms, a pair of ribbon-spool-rotating devices supported from the shift frame at opposite sides of the machine forward of the shift frame, a second rock shaft extending transversely of the machine forward of the shift frame and journalled on the main frame, a connection between said second rock shaft and one of the universal-bar-carrying arms for rocking said shaft, separate operating connections between said second rock shaft and said spool-rotating devices, and mechanism forward of the shift frame and supported therefrom for rendering the spool-rotating devices effective alternately and operable alternately from a part of each of said operating connections to the spool-rotating devices.

13. In a typewriting machine, a main frame, a platen carriage, an up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type-bars for actuating said universal bar, a pair of transversely spaced arms carrying said universal bar at their forward ends and having longitudinally extending guide slots at their rear ends through which said rock shaft extends, said universal-bar-carrying arms extending through the shift frame and supported and guided on the rock shaft between the rock arms, fore-and-aft swinging means mounted on the main frame between the rock shaft and universal bar and pivotally connected with said universal-bar-carrying arms forward of the rock shaft for supporting and guiding said arms, an arm depending from one of said universal-bar-carrying arms, a second transverse rock shaft journalled on the main frame forward of the shift frame, a rock arm depending from said shaft, a fore-and-aft extending link connecting said depending arms, and ribbon feeding and vibrating devices supported from the shift frame forwardly of the shift frame and operable from said second rock shaft.

14. In a typewriting machine, a main frame, a platen carriage, an up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type bars for actuating said universal bar, a pair of transversely spaced arms carrying said universal bar at their forward ends and having longitudinally extending guide slots at their rear ends through which said rock shaft extends, said universal-bar-carrying arms extending through the shift frame and supported and guided on the rock shaft between the rock arms, fore-and-aft swinging means mounted on the main frame between the rock shaft and universal bar and pivotally connected with said universal-bar-carrying arms forward of the rock shaft for supporting and guiding said arms, an arm depending from one of said universal-bar-carrying arms, a second transverse rock shaft journalled on the main frame forward of the shift frame, a rock arm depending from said shaft, a fore-and-aft extending link connecting said depending arms, and ribbon feeding and vibrating devices supported from the shift frame forwardly of the shift frame and operable from said second rock shaft.

15. In a typewriting machine, a main frame, a platen carriage, an up-and-down movable shift frame supporting the carriage, a transverse rock shaft journalled on the main frame in rear of the shift frame, a pair of rock arms extending forward from said shaft and connected with the shift frame for moving the shift frame up and down, shift key-operated means for rocking said shaft, an arcuate universal bar forward of the shift frame, key-operated type bars for actuating said universal bar, a pair of transversely spaced arms carrying said universal bar at their forward ends and having longitudinally extending guide slots at their rear ends

- through which said rock shaft extends, said universal-bar-carrying arms extending through the shift frame and supported and guided on the rock shaft between the rock 5 arms, fore-and-aft swinging means mounted on the main frame between the rock shaft and universal bar and pivotally connected with said universal-bar-carrying arms forward of the rock shaft for supporting and 10 guiding said arms, an arm depending from one of said universal-bar-carrying arms, a second transverse rock shaft journaled on the main frame forward of the shift frame, a rock arm depending from said shaft, a fore- 15 and-aft extending link connecting said depending arms, ribbon feeding and vibrating devices supported from the shift frame forwardly of the shift frame and operable from said second rock shaft, a dog rocker for the 20 carriage escapement supported from the shift frame in rear of the universal bar and ribbon feeding and vibrating devices, and an actuator for the dog rocker on the universal-bar-carrying arm opposite that arm from 25 which the second rock shaft is actuated.
16. In a typewriting machine, a main frame, a platen carriage, an up-and-down movable shift frame supporting the carriage, a transverse rock shaft journaled on the main 30 frame in rear of the shift frame, a pair of rock arms extending forward from said shaft and connected with the shift frame for moving the shift frame up-and-down, shift key operated means for rocking said shaft, an arcuate universal bar forward of the shift frame, key-operated type bars for actuating 35 said universal bar, a pair of transversely spaced arms carrying said universal bar at their forward ends and having longitudinally 40 extending guide slots at their rear ends through which said rock shaft extends, said universal-bar-carrying arms extending through the shift frame and supported and guided on the rock shaft between the rock 45 arms, fore-and-aft swinging means mounted on the main frame between the rock shaft and universal bar and pivotally connected with said universal-bar-carrying arms forward of the rock shaft for supporting and 50 guiding said arms, a ribbon mechanism actuating means mounted on the main frame forward of the shift frame, an operating connection between said actuating means and one of the universal-bar-carrying arms, and 55 an escapement actuator on the other one of said universal-bar-carrying arms in rear of the shift frame.
17. In a typewriting machine, a main frame, a platen carriage, an up-and-down movable shift frame supporting the carriage, a transverse rock shaft journaled on the main frame in rear of the shift frame, a pair of rock arms extending forward from said shaft and connected with the shift frame 60 for moving the shift frame up-and-down, shift key-operated means for rocking said shaft, an arcuate universal bar forward of the shift frame, key-operated type bars for actuating said universal bar, a pair of transversely spaced arms carrying said universal bar at their forward ends and having longitudinally 65 extending guide slots at their rear ends through which said rock shaft extends, said universal-bar-carrying arms extending through the shift frame and supported and guided on the rock shaft between the rock 70 arms, fore-and-aft swinging means mounted on the main frame between the rock shaft and universal bar and pivotally connected with said universal-bar-carrying arms forward of the rock shaft for supporting and 75 guiding said arms, ribbon-mechanism-actuating means connected with one of said universal-bar-carrying arms, and an escapement mechanism actuating means connected with 80 the other universal-bar-carrying arm.
18. In a typewriting machine, a main frame, a platen carriage, an up-and-down movable shift frame supporting the carriage, a transverse rock shaft journaled on the main frame in rear of the shift frame, a pair of rock arms extending forward from said shaft and connected with the shift frame for moving the shift frame up and down, shift key-operated means for rocking said 85 shaft, an arcuate universal bar forward of the shift frame, key-operated type bars for actuating said universal bar, a pair of transversely spaced arms carrying said universal bar at their forward ends and having longitudinally 90 extending guide slots at their rear ends through which said rock shaft extends, said universal-bar-carrying arms extending through the shift frame and supported and guided on the rock shaft between the rock 95 arms, fore-and-aft swinging means mounted on the main frame between the rock shaft and universal bar and pivotally connected with said universal-bar-carrying arms forward of the rock shaft for supporting and 100 guiding said arms, an escapement actuator mounted on one of said universal-bar-carrying arms at the rear of the shift frame, and a space-bar-operated escapement actuator having a pin-and-slot supporting and guiding 105 connection with said fore-and-aft swinging means and extending through the shift frame.
19. In a typewriting machine, an arcuate type-bar-actuated universal bar, a pair of fore-and-aft extending arms carrying said universal bar at their forward ends, means supporting said arms to vibrate endwise, an escapement actuator carried by one of said arms, and an actuating arm for the ribbon mechanism of the machine carried by the other one of said arms.
20. In a typewriting machine, key-operated rearwardly-striking type bars, a fore-and-aft vibratable universal bar operable by 110

the type bars, a fore-and-aft rocking support for the universal bar, ribbon vibrating means and ribbon feeding means both connected with said universal bar for operation thereby, 5 escapement mechanism, an actuator for the escapement mechanism positively connected with the universal bar to vibrate fore-and-aft therewith, a space bar, and a second actuator for the escapement mechanism positively 10 connected at its forward end with the space bar for fore-and-aft vibration thereby and having a fore-and-aft sliding connection with said rocking support adjacent its rear end, said actuators having a push connection only 15 with the escapement mechanism.

21. In a typewriting machine, a main frame, a platen carriage, a platen on the carriage, a shift frame for the platen carriage, means for shifting said frame including a 20 rock shaft journaled on the main frame, a key-lever-fulcrum support mounted on the main frame, character key levers fulcrumed on said fulcrum support, type bars operable by the key levers, a rocker mounted on said 25 fulcrum support to vibrate fore-and-aft of the machine, a universal bar operable by the type bars, supporting arms spaced apart transversely of the machine carrying said universal bar at their forward ends and having longitudinal guide slots at their rear ends 30 through which said rock shaft extends to support and guide said bars, and means pivotally connecting said universal-bar-carrying arms with said rocker between the universal bar 35 and said rock shaft.

22. In a typewriting machine, a type bar actuated universal bar, a pair of fore-and-aft swinging arms spaced apart transversely of the machine in rear of said bar, said bar having a pair of integral forward side arm 40 members extending rearward therefrom and pivotally held intermediate their ends to said swinging arms, a pair of rear side arm members detachably secured at their forward ends 45 to the rear portions of said forward side arm members and having longitudinally slotted rear ends, means on the main frame extending through the slots in said rear side arm members to cooperate with the swinging 50 arms to guide and support the universal bar, the rear member of one side arm being formed with an integral depending arm for actuating the ribbon mechanism of the machine, and the front member of the other side arm 55 being formed with an integral tappet extending in an up-and-down direction for actuating the escapement mechanism of the machine.

23. In a typewriting machine, a type bar 60 actuated universal bar, a pair of fore-and-aft swinging arms spaced apart transversely of the machine in rear of said bar, said bar having a pair of integral forward side arm members extending rearward therefrom and 65 pivotally held intermediate their ends to said

swinging arms, a pair of rear side arm members detachably secured at their forward ends to the rear portions of said forward side arm members, and having longitudinally slotted rear ends, means on the main frame extending through the slots in said rear side arm members to cooperate with the swinging arms to guide and support the universal bar, the rear member of one side arm being formed with an integral depending arm for actuating the ribbon mechanism of the machine, the front member of the other side arm being formed with an integral tappet extending in an up-and-down direction for actuating the escapement mechanism of the machine, and 70 one of said rear side arm members carrying an integral transversely extending spacer bar abutting the inner face of the other rear side arm member. 75

24. In a typewriting machine, an arcuate type-bar-actuated universal bar, side arms extending rearward from said universal bar, means supporting said side arms to vibrate back and forth and located to the rear of the universal bar, an escapement actuator carried 90 by one of said side arms, a ribbon mechanism operating arm depending from the other side arm, a rock shaft extending transversely of the machine under the universal bar, a rock arm depending from said shaft, a link extending rearward from said depending rock arm and connected with said depending ribbon mechanism operating arm, a pair of up-standing actuators held to said rock shaft to vibrate fore-and-aft at opposite ends of the 95 universal bar, a pair of ribbon spool rotating devices adjacent opposite sides of the machine operable from said actuators, a pair of devices adjacent opposite sides of the machine operable from said actuators to render the rotating device for one spool ineffective when the ribbon is exhausted from the other spool, a ribbon vibrating device, and an actuator for said device held to said rock shaft adjacent one side of the machine. 100

25. In a typewriting machine, an arcuate type-bar-actuated universal bar, side arms extending rearward from said universal bar, means supporting said side arms to vibrate back and forth and located to the rear of the universal bar, an escapement actuator carried by one of said side arms, a ribbon mechanism operating arm depending from the other side arm, a rock shaft extending transversely of the machine under the universal bar, a rock arm depending from said shaft, a link extending from said depending rock arm and connected with said depending ribbon mechanism operating arm, a pair of up-standing actuators held to said rock shaft to vibrate fore-and-aft at opposite ends of the universal bar, a pair of ribbon spool rotating devices adjacent opposite sides of the machine operable from said actuators, a pair of devices adjacent opposite sides of the ma- 110 115 120 125 130

chine operable from said actuators to render the rotating device for one spool ineffective when the ribbon is exhausted from the other spool, a ribbon vibrating device, an actuator for said device held to said rock shaft adjacent one side of the machine, a second rock arm depending from said rock shaft, and a return spring for said universal bar and rock shaft connected with said last-
10 mentioned rock arm.

26. In a typewriting machine, a platen, a platen carriage, a main frame having an upwardly and rearwardly inclined transverse partition wall the lower edge of which is located above the base line of the main frame, an arcuate universal bar located forward of said wall, a type bar segment held to the front face of said wall having a recess in its rear face in which said universal bar
15 vibrates, supporting arms extending rearward and downward from the universal bar through said wall, means in rear of said wall supporting said side arms to vibrate endwise, a transverse rock shaft closely underlying said partition wall, two arms depending respectively from said rock shaft and one of said side arms, a fore-and-aft extending link connecting said two depending arms, type bars pivoted in the segment and
20 adapted to move the universal bar rearwardly and downwardly on their printing strokes, key-operated means for actuating the type bars, escapement mechanism for the platen carriage located to the rear of the
25 plane of said partition wall, an actuator for the escapement carried by one of said side arms in rear of the partition wall, ribbon vibrating means located forwardly of the plane of said partition wall, and an actuator for said ribbon vibrating means held to the rock shaft.

27. In a typewriting machine, a platen, a platen carriage, a main frame having an upwardly and rearwardly inclined transverse partition wall the lower edge of which is located above the base line of the main frame, an arcuate universal bar located forward of said wall, a type bar segment held to the front face of said wall having a recess in its rear face in which said universal bar vibrates, supporting arms extending rearward and downward from the universal bar through said wall, means in rear of said wall supporting said side arms to vibrate endwise, a transverse rock shaft closely underlying said partition wall, two arms depending respectively from said rock shaft and one of said side arms, a fore-and-aft extending link connecting said two depending arms, type bars pivoted in the segment and
30 adapted to move the universal bar rearwardly and downwardly on their printing strokes, key-operated means for actuating the type bars, escapement mechanism for the platen carriage located to the rear of the plane of said partition wall, an actuator for the escapement carried by one of said side arms in rear of the partition wall, ribbon vibrating means located forwardly of the plane of said partition wall, an actuator for said ribbon
35 vibrating means held to the rock shaft, a space bar, and an independent actuator for the escapement mechanism operable by said space bar and extending under said partition wall and rock shaft.

29. In a typewriting machine, a platen, means for case-shifting the platen including a rock shaft extending transversely of the machine, an arcuate universal bar, endwise movable side arms carrying said universal bar at their forward ends, means for supporting and guiding said side arms including longitudinal slots in said arms in which said rock shaft is engaged, key-operated type bars adapted to move said universal bar rearward on their printing strokes, a segment in which the type bars are pivoted, a return spring for the universal bar, and means for limiting the throw of the universal bar including said rock shaft and said segment.

30. In a typewriting machine, a platen, means for case-shifting the platen including a rock shaft extending transversely of the machine, an arcuate universal bar having rearwardly extending supporting arms, means for guiding said arms to move end-
130

plane of said partition wall, an actuator for the escapement carried by one of said side arms in rear of the partition wall, ribbon vibrating mechanism located forwardly of the plane of said partition wall, an actuator for
70 said ribbon vibrating means held to the rock shaft, ribbon feeding mechanism located forward of the plane of said partition wall, and means held to said rock shaft for actuating said ribbon feeding mechanism.

28. In a typewriting machine, a platen, a platen carriage, a main frame having an upwardly and rearwardly inclined transverse partition wall the lower edge of which is located above the base line of the main frame, an arcuate universal bar located forward of said wall, a type bar segment held to the front face of said wall having a recess in its rear face in which said universal bar vibrates, supporting arms extending rearward and downward from the universal bar through said wall, means in rear of said wall supporting said side arms to vibrate endwise, a transverse rock shaft closely underlying said partition wall, two arms depending respectively from said rock shaft and one of said side arms, a fore-and-aft extending link connecting said two depending arms, type bars pivoted in the segment and adapted to move the universal bar rearwardly and
85 downwardly on their printing strokes, key-operated means for actuating the type bars, escapement mechanism for the platen carriage located to the rear of the plane of said partition wall, an actuator for the escapement carried by one of said side arms in rear of the partition wall, ribbon vibrating mechanism located forwardly of the plane of said partition wall, an actuator for said ribbon
90 vibrating means held to the rock shaft, a space bar, and an independent actuator for the escapement mechanism operable by said space bar and extending under said partition wall and rock shaft.

29. In a typewriting machine, a platen, means for case-shifting the platen including a rock shaft extending transversely of the machine, an arcuate universal bar, endwise movable side arms carrying said universal bar at their forward ends, means for supporting and guiding said side arms including longitudinal slots in said arms in which said rock shaft is engaged, key-operated type bars adapted to move said universal bar rearward on their printing strokes, a segment in which the type bars are pivoted, a return spring for the universal bar, and means for limiting the throw of the universal bar including said rock shaft and said segment.

30. In a typewriting machine, a platen, means for case-shifting the platen including a rock shaft extending transversely of the machine, an arcuate universal bar having rearwardly extending supporting arms, means for guiding said arms to move end-
130

wise including longitudinal slots in said arms through which said shaft extends, key-operated type bars adapted to engage said universal bar and move it rearward on their printing strokes, and an overthrow stop for the universal bar carried by one of said side arms and adapted to engage said rock shaft.

31. In a typewriting machine, a platen carriage including a dog rocker mounted to swing about an axis extending transversely of the machine, an arcuate universal bar, key-operated type bars for actuating the universal bar, a rigid member extending rearward from the universal bar having its rear end arranged to engage and rock the dog rocker, a fore-and-aft swinging supporting arm for the universal bar mounted on the framework of the machine and pivotally connected with said rigid member, a transverse rock shaft journaled on the framework of the machine forward of said supporting arm, a rock arm held to said shaft to swing fore-and-aft of the machine, a space bar connected with said shaft for rocking the shaft, a laterally projecting stud on said supporting arm, a second rigid member extending fore-and-aft of the machine having its rear end arranged to engage and rock the dog rocker and provided with a fore-and-aft extending guide slot through which said stud extends and pivotally connected at its forward end with said rock arm.

32. In a typewriting machine, a platen carriage, escapement mechanism for the carriage including a dog rocker mounted to swing about an axis extending transversely of the machine, an arcuate universal bar, key-operated type bars for actuating the universal bar, a rigid member extending rearward from the universal bar having its rear end arranged to engage and rock the dog rocker, a fore-and-aft swinging supporting arm for the universal bar mounted on the framework of the machine and pivotally connected with said rigid member, a transverse rock shaft journaled on the framework of the machine forward of said supporting arm, a rock arm held to said shaft to swing fore-and-aft of the machine, a space bar connected with said shaft for rocking the shaft, a laterally projecting stud on said supporting arm, a second rigid member extending fore-and-aft of the machine having its rear end arranged to engage and rock the dog rocker and provided with a fore-and-aft extending guide slot through which said stud extends and pivotally connected at its forward end with said rock arm, and a fore-and-aft extending return spring for the space bar and said second rigid member connected with said member at its rear end and connected at its forward end with the framework of the machine.

33. In a typewriting machine, a platen carriage, escapement mechanism for the car-

riage including a dog rocker mounted to swing about an axis extending transversely of the machine, an arcuate universal bar, key-operated type bars for actuating the universal bar, a rigid member extending rearward from the universal bar having its rear end arranged to engage and rock the dog rocker, a fore-and-aft swinging supporting arm for the universal bar mounted on the framework of the machine and pivotally connected with said rigid member, a transverse rock shaft journaled on the framework of the machine forward of said supporting arm, a rock arm held to said shaft to swing fore-and-aft of the machine, a space bar connected with said shaft for rocking the shaft, a laterally projecting stud on said supporting arm, a second rigid member extending fore-and-aft of the machine having its rear end arranged to engage and rock the dog rocker and provided with a fore-and-aft extending guide slot through which said stud extends and pivotally connected at its forward end with said rock arm, and a ribbon vibrating mechanism operable by said universal bar.

34. In a typewriting machine, a platen carriage, escapement mechanism for the carriage including a dog rocker mounted to swing about an axis extending transversely of the machine, an arcuate universal bar, key-operated type bars for actuating the universal bar, a rigid member extending rearward from the universal bar having its rear end arranged to engage and rock the dog rocker, a fore-and-aft swinging supporting arm for the universal bar mounted on the framework of the machine and pivotally connected with said rigid member, a transverse rock shaft journaled on the framework of the machine forward of said supporting arm, a rock arm held to said shaft to swing fore-and-aft of the machine, a space bar connected with said shaft for rocking the shaft, a laterally projecting stud on said supporting arm, a second rigid member extending fore-and-aft of the machine having its rear end arranged to engage and rock the dog rocker and provided with a fore-and-aft extending guide slot through which said stud extends and pivotally connected at its forward end with said rock arm, a fore-and-aft extending return spring for the space bar and said second rigid member connected with said member at its rear end and connected at its forward end with the framework of the machine, and a ribbon feeding and vibrating means operable by said universal bar.

35. In a typewriting machine, a platen carriage, escapement mechanism for the carriage including a dog rocker mounted to swing about an axis extending transversely of the machine, an arcuate universal bar, key-operated type bars for actuating the universal bar, a rigid member extending rearward from the universal bar having its rear end ar-

- ranged to engage and rock the dog rocker, a fore-and-aft swinging supporting arm for the universal bar mounted on the framework of the machine and pivotally connected with 5 said rigid member, a transverse rock shaft journalled on the framework of the machine forward of said supporting arm, a rock arm held to said shaft to swing fore-and-aft of the machine, a space bar connected with said 10 shaft for rocking the shaft, a laterally projecting stud on said supporting arm, a second rigid member extending fore-and-aft of the machine having its rear end arranged to engage and rock the dog rocker and provided 15 with a fore-and-aft extending guide slot through which said stud extends and pivotally connected at its forward end with said rock arm, and means for shifting the carriage up and down to change case, said dog 20 rocker being mounted to partake of case shift movements of the platen carriage and having a laterally extending lug, and the rear ends of said rigid dog-rocker-actuating members having rearwardly facing rear end edges extending parallel with the path of shift of the 25 carriage and dog rocker and adapted to engage said dog rocker lug in all case positions of the carriage.
36. In a typewriting machine, a platen carriage, escapement mechanism for the carriage including a dog rocker mounted to swing about an axis extending transversely of the machine, an arcuate universal bar, key-operated type bars for actuating the universal bar, a rigid member extending rearward from the universal bar having its rear end arranged to engage and rock the dog rocker, a fore-and-aft swinging supporting arm for the universal bar mounted on the framework 30 of the machine and pivotally connected with said rigid member, a transverse rock shaft journalled on the framework of the machine forward of said supporting arm, a rock arm held to said shaft to swing fore-and-aft of the machine, a space bar connected with said 35 shaft for rocking the shaft, a laterally projecting stud on said supporting arm, a second rigid member extending fore-and-aft of the machine having its rear end arranged to engage and rock the dog rocker and provided 40 with a fore-and-aft extending guide slot through which said stud extends and pivotally connected at its forward end with said rock arm, ribbon mechanism operable by said 45 universal bar, and means for shifting the carriage up and down to change case, said dog 50 rocker being mounted to shift with the carriage and having an abutment located a fixed distance from its pivot engageable by the rear 55 end edges of said two rigid members in all case positions of the carriage, said end edges of said members extending parallel with the path of case shift movement of the carriage.
37. In a three-quarter strike typewriting 60 machine, a platen, a platen carriage, an ob- lique shiftable shift frame supporting the carriage, key-operated means for shifting the shift frame, a main frame, type bars pivotally mounted on the main frame to strike on the upper front quarter of the platen with 65 their pivots in a plane parallel with the plane of movement of the shift frame, character keys, connections between the character keys and type bars for actuating the type bars, ribbon feeding and vibrating means supported from the shift frame forwardly of said shift frame, escapement means for the carriage located entirely to the rear of said type bars and their operating connections and entirely to the rear of said ribbon feeding and 70 vibrating means and shiftable with the shift frame, and type-bar-operated universal bar mechanism mounted on the main frame for actuating said escapement means and said ribbon feeding and vibrating means.
38. In a typewriting machine, a main frame, a shift frame guided to move up and down in the main frame, a transverse rock shaft journalled in the main frame in rear of the shift frame, rock arms connecting said shaft with the shift frame, shift-key-operated means for rocking said shaft, a key-lever fulcrum member mounted on the main frame forward of the shift frame, an arcuate universal bar forward of the shift frame, side 85 arms carrying said universal bar at their forward ends extending through the shift frame and provided with longitudinal guide slots through which said rock shaft extends, a pair of fore-and-aft swinging supporting arms mounted on said fulcrum member and pivotally connected with said side arms, key levers fulcrumed at their rear ends on said fulcrum member, a system of type bars pivoted on the main frame forward of the shift frame and 90 adapted to engage and operate the universal bar on their printing strokes, operating connections between the key levers and type bars, a platen carriage on the shift frame, a platen on the carriage, escapement mechanism shiftable with the shift frame, ribbon feeding and vibrating means located forwardly of and shiftable with the shift frame, an actuator for said ribbon feeding and vibrating means mounted on the main frame 95 forward of the shift frame and connected with one of said side arms, and an actuator for the escapement mechanism located in rear of the shift frame and carried by the other 100 one of said side arms.
39. In a typewriting machine, a main frame, a shift frame guided to move up and down in the main frame, a transverse rock shaft journalled in the main frame in rear of the shift frame, rock arms connecting said shaft with the shift frame, shift-key-operated means for rocking said shaft, a key-lever fulcrum member mounted on the main frame forward of the shift frame, an arcuate universal bar forward of the shift frame, side 110
- 65 machine, a platen, a platen carriage, an ob- 115

arms carrying said universal bar at their forward ends extending through the shift frame and provided with longitudinal guide slots through which said rock shaft extends, a pair 5 of fore-and-aft swinging supporting arms mounted on said fulcrum member and pivotally connected with said side arms, key levers fulcrumed at their rear ends on said fulcrum member; a system of type bars pivoted on the 10 main frame forward of the shift frame and adapted to engage and operate the universal bar on their printing strokes, operating connections between the key levers and type bars, a platen carriage on the shift frame, a platen 15 on the carriage, and escapement means and ribbon feeding and vibrating means all shiftable with the shift frame and operable from said universal bar.

40. In a three-quarter strike typewriting 20 machine, a slotted type bar segment, an arcuate type bar-operated universal bar behind said segment, said segment and universal bar lying in an upwardly and rearwardly inclined plane, a platen above and in rear of 25 the segment, type bars pivoted in the segment slots to strike on the upper front quarter of the platen and actuate said universal bar on their printing strokes, key-operated 30 means for actuating the type bars, means in rear of the segment supporting the universal bar to vibrate back and forth in a downwardly and rearwardly inclined path, a transverse rock shaft below the segment, a pair of upstanding rock arms held to said 35 shaft between which the segment and universal bar extend, ribbon feeding mechanism operable by said upstanding rock arms, ribbon vibrating means, an actuator for said vibrating means on said rock shaft, a rock arm 40 depending from said rock shaft, a connection between said rock arm and universal bar for rocking the shaft, a carriage for the platen, and escapement mechanism for the carriage operable from said universal bar.

45. In a typewriting machine, a main 45 frame, a platen carriage, a platen on the carriage, a key lever fulcrum support held to the main frame, character key levers pivotally held to said support, type bars operable by the key levers, an anchor bar on the main frame, key lever return springs connected with said anchor and the key levers, an arcuate universal bar operable by the type bars, a rocking support for the universal bar 50 mounted on said key-lever fulcrum support, escapement mechanism operable by said universal bar, a transverse rock shaft journaled in the main frame, a pair of rock arms on said shaft, a positive connection between the universal bar and one of said rock arms for turning the shaft in one direction on the printing strokes of the type bars, a spring connected with the other rock arm and with said anchor bar for turning the shaft in the opposite direction and returning the universal bar on the return strokes of the type bars, ribbon vibrating mechanism operable from said rock shaft, an actuator for the carriage escapement operable independently of said universal bar, a space bar for moving said actuator in one direction, and a return spring for said space 55 bar and actuator connecting the actuator with said anchor bar.

60. In a typewriting machine, a main frame, a platen, a platen carriage, a key lever fulcrum support on the main frame, character key levers fulcrumed on said support, type bars operable by the key levers, an anchor bar on the main frame, key lever return springs connected with said anchor and the key levers, an arcuate universal bar oper- 65

versal bar on the return strokes of the type bars, and ribbon vibrating mechanism operable from said rock shaft.

42. In a typewriting machine, a main frame; a platen carriage, a platen on the carriage, a key lever fulcrum support on the main frame, character key levers pivotally held to said support, type bars operable by the key levers, an anchor bar on the main frame, key lever return springs connected with said anchor and the key levers, an arcuate universal bar operable by the type bars, a rocking support for the universal bar mounted on said key-lever fulcrum support, escapement mechanism operable by said universal bar, a transverse rock shaft journaled in the main frame, a pair of rock arms on said shaft, a positive connection between the universal bar and one of said rock arms for turning the shaft in one direction on the printing strokes of the type bars, a spring connected with the other rock arm and with said anchor bar for turning the shaft in the opposite direction and returning the universal bar on the return strokes of the type bars, and ribbon feeding and reversing mechanism and ribbon vibrating mechanism all operable from said shaft.

43. In a typewriting machine, a main frame, a platen, a platen carriage, a key lever fulcrum support on the frame, character key levers pivotally held to said support, type bars operable by the key levers, an anchor bar on the main frame, key lever return springs connected with said anchor and the key levers, an arcuate universal bar operable by the type bars, a rocking support for the universal bar mounted on said key-lever fulcrum support, escapement mechanism operable by said universal bar, a transverse rock shaft journaled in the main frame, a pair of rock arms on said shaft, a positive connection between the universal bar and one of said rock arms for turning the shaft in one direction on the printing strokes of the type bars, a spring connected with the other rock arm and with said anchor bar for turning the shaft in the opposite direction and returning the universal bar on the return strokes of the type bars, ribbon vibrating mechanism operable from said rock shaft, an actuator for the carriage escapement operable independently of said universal bar, a space bar for moving said actuator in one direction, and a return spring for said space bar and actuator connecting the actuator with said anchor bar.

44. In a typewriting machine, a main frame, a platen, a platen carriage, a key lever fulcrum support on the main frame, character key levers fulcrumed on said support, type bars operable by the key levers, an anchor bar on the main frame, key lever return springs connected with said anchor and the key levers, an arcuate universal bar oper-

- able by the type bars, a rocking support for the universal bar mounted on said key-lever fulcrum support, escapement mechanism operable by said universal bar, a transverse 5 rock shaft journalled in the main frame, a pair of rock arms on said shaft, a positive connection between the universal bar and one of said rock arms for turning the shaft in one direction on the printing strokes of the type 10 bars, a spring connected with the other rock arm and with said anchor bar for turning the shaft in the opposite direction and returning the universal bar on the return strokes of the type bars, ribbon vibrating mechanism operable 15 from said rock shaft, an actuator for the carriage escapement operable independently of said universal bar, a space bar for moving said actuator in one direction, a return spring for said space bar and actuator connecting the 20 actuator with said anchor bar, said actuator having a pin-and-slot supporting and guiding connection with said rocking support for the universal bar.
45. In a typewriting machine, a main 25 frame having an upwardly and rearwardly inclined transverse partition wall, a type bar segment held to the front face of said wall, a platen carriage above and in rear of the segment, a platen on the carriage, a fulcrum 30 member held to the rear face of said wall, key levers extending under said wall and fulcrumed on said member, type bars pivoted in said segment to strike on the upper front quarter of the platen, operating connections 35 between the key levers and type bars, a transverse rock shaft, bearings for said rock shaft held to said wall, an arcuate universal bar operable by the type bar located forward of said wall, side arms extending rearward and 40 downward through said wall carrying said universal bar at their forward ends, a rocking support mounted on said fulcrum member and to which said side arms are pivoted, means engaged with the side arms adjacent 45 their rear ends and cooperating with said rocking support to guide the universal bar to move rearwardly and downwardly, fore-and-aft spaced arms depending from said rock shaft and one of said side arms, a link connecting said spaced arms, a bichrome ribbon 50 vibrating device operable from said rock shaft and connected therewith at one side of the type bars, ribbon spool rotating devices operable from said rock shaft and connected 55 therewith at opposite sides of the type bars, and escapement mechanism operable from the universal bar.
46. In a typewriting machine, a main 60 frame, a shift frame, a platen carriage on the shift frame, a platen on the carriage, an arcuate universal bar, counterbalancing means for the shift frame including a transverse rock shaft journalled on the main frame in rear of the universal bar, side arms carrying said 65 universal bar at their forward ends and slid- ably guided on said rock shaft at their rear ends to move fore-and-aft of the machine, fore-and-aft swinging means for supporting said side arms fulcrumed on the main frame and pivotally connected with said side arms 70 between the universal bar and rock shaft, key-operated type bars pivoted on the main frame and adapted to move the universal bar rearwardly on their printing strokes, and carriage feeding, ribbon feeding, and ribbon vibrating means all operable from said universal bar.
47. In a typewriting machine, a platen carriage, a platen thereon, a pair of ribbon spools, independent spool rotating devices for 80 said spools, a pair of tappets, automatic reversing mechanism for rendering said devices alternately effective operable by said tappets, operating connections from said tappets to different ones of said independent spool rotating devices, a third tappet, ribbon vibrating means operable by said third tappet, a fourth tappet, escapement mechanism for the carriage operable by said fourth tappet, key-operated type bars, and a universal bar actuated by the type bars and operatively connected with all of said tappets for actuating the tappets at the type bar strokes.
48. In a typewriting machine, a platen carriage; a platen thereon; ribbon vibrating mechanism, including bichrome shift and stenciling means; ribbon feeding means; reversing mechanism for the ribbon feed; escapement mechanism for the carriage; a universal bar for actuating the carriage escapement; key-operated type bars arranged to actuate said universal bar; a rock shaft operable by said universal bar, tappet means on said rock shaft for actuating both said ribbon feeding means and its reversing mechanism; and tappet means on said shaft for actuating said ribbon vibrating mechanism.
49. In a typewriting machine, a main frame, a platen carriage, a platen on the carriage, means for case-shifting the carriage, key-operated type bars on the main frame, carriage feeding means shiftable with the carriage, ribbon feeding means shiftable with the carriage, ribbon feed reversing means shiftable with the carriage, ribbon vibrating means shiftable with the carriage, and separate type-bar-actuated tappet devices on the main frame operatively associated respectively with said carriage feeding, ribbon feed reversing, and ribbon vibrating means for actuating the same in all case positions of the platen carriage.
50. In a typewriting machine, a main frame, a platen carriage, a platen on the carriage, means for case-shifting the platen 125 carriage, key-operated type bars on the main frame, a universal bar on the main frame operable by the type bars, a rock shaft on the main frame operable from said universal bar, a pair of independent ribbon-spool-rotating 130

devices shiftable with the carriage, a pair of rock arms on said shaft, an operating connection between each rock arm and one of said spool-rotating devices, a tappet on each of said 5 rock arms, feed-reversing mechanism shiftable with the carriage and operable by said tappets for rendering one of said spool-rotating devices effective at a time, ribbon vibrating means shiftable with the carriage, 10 a third rock arm on said shaft, a tappet on said third rock arm for actuating said ribbon vibrating mechanism, escapement mechanism for the carriage shiftable therewith, and a tappet held to the universal bar for actuating 15 said escapement mechanism.

51. In a typewriting machine, a main frame, a platen carriage shiftable to change case, a platen on the carriage, ribbon spools and driving means therefor shiftable with 20 the carriage, a ribbon guide and vibrating means therefor shiftable with the carriage, a carriage escapement shiftable with the carriage, key-operated type bars on the main frame, an arcuate universal bar operable 25 directly by the type bars, vibratory supporting means for the universal bar on the main frame, means for transmitting motion from one side of said vibratory universal bar supporting means to said spool driving means 30 and said ribbon guide vibrating means, and means for transmitting motion from the opposite side of said vibratory universal bar supporting means to said escapement.

52. In a typewriting machine, a main frame, key-operated type bars on the main frame, a platen, means for case-shifting the platen including a rock shaft extending transversely of the machine and journaled in the main frame, a universal bar operable 40 directly by the type bars and having fore and aft extending side arms slidably guided on said rock shaft to move endwise, fore and aft swinging rock arms pivotally held to said side arms and the main frame to cooperate 45 with said shaft in supporting and guiding the universal bar, ribbon feeding and vibrating means operable by said universal bar, and means for letter spacing the platen operable by said universal bar.

53. In a typewriting machine, a main frame, a platen carriage, a platen on the carriage, a support for the carriage shiftable to change case, key-operated type bars on the main frame, a universal bar mounted on 55 the main frame and operable directly by the type bars, ribbon spools and a carriage escapement carried by the shiftable carriage support, said escapement being operable by said universal bar, ribbon spool rotating 60 devices and ribbon-set feed reversing means associated therewith and all carried by the shiftable carriage support, a transverse rock shaft journaled in the main frame connected with said universal bar for rocking thereby, 65 a pair of rock arms held to said shaft, links

connecting said rock arms with the respective spool rotating devices, and a pair of tappets carried by said rock arms for alternately actuating the feed-reversing means.

54. In a typewriting machine, a main 70 frame, a platen carriage, a platen on the carriage, a shift frame supporting the carriage, a transverse rock shaft journaled on the main frame, a pair of rock arms held to said shaft and connected with the shift frame for 75 shifting said frame, shift-key-operated means for rocking said shaft, key-operated type bars, a universal bar vibratable fore and aft of the machine by the keys and having transversely spaced fore and aft slotted portions 80 through which said rock shaft extends, fore and aft rocking supporting means mounted on the main frame and pivotally connected with said universal bar, ribbon feeding means operable by said universal bar; and ribbon 85 vibrating and carriage escapement devices shiftable with the shift frame and operable by said universal bar.

55. In a typewriting machine, a main frame, a platen carriage, a platen on the carriage, a shift frame supporting the carriage, a transverse rock shaft journaled on the main frame, a pair of rock arms held to said shaft and connected with the shift frame for shifting said frame, shift-key-operated means for 90 rocking said shaft, key-operated-type bars, a universal bar vibratable fore and aft of the machine by the keys and having transversely spaced fore and aft slotted portions through 95 which said rock shaft extends, fore and aft rocking supporting means mounted on the main frame and pivotally connected with said universal bar, and a ribbon vibrator actuator mounted on the main frame independently of and operatively connected with the universal 100 bar.

56. In a typewriting machine, a main frame, a platen carriage, a platen on the carriage, a shift frame supporting the carriage, a transverse rock shaft journaled on the main frame, a pair of rock arms held to said shaft and connected with the shift frame for shifting said frame, shift-key-operated means for 110 rocking said shaft, key-operated type bars, a universal bar vibratable fore and aft of the machine by the keys and having transversely spaced fore and aft slotted portions through 115 which said rock shaft extends, fore and aft rocking supporting means mounted on the main frame and pivotally connected with said universal bar, and a common actuator for a pair of ribbon spool driving devices mounted 120 on the main frame independently of and operatively connected with the universal bar.

57. In a typewriting machine, a main frame, a platen carriage, a platen on the carriage, a key lever fulcrum support held to the main frame, character key levers pivotally held to said support, type bars operable by 125 the key levers, an anchor bar on main frame, 130

key lever return springs connected with said anchor bar and the key levers, a universal bar operable by the type bars, a rocking support for the universal bar mounted on said 5 key lever fulcrum support, a carriage escapement operable by the universal bar, a transverse rock shaft journaled in the main frame, a pair of rock arms on said shaft, an operating connection between the universal bar 10 and one of said rock arms for turning the shaft in one direction on the printing strokes of the type bars, a spring connecting the other rock arm with the anchor bar for rotating the shaft in the opposite direction and 15 returning the universal bar on the return strokes of the type bars, and ribbon feeding mechanism operable from said rock shaft.

58. In a typewriting machine, a main frame, a platen carriage, a platen on the carriage, means for case-shifting the carriage,

key-operated type bars on the main frame, a universal bar on the main frame operable by the type bars, a rock shaft on the main frame operable by said universal bar, a pair of independent spool rotating devices and a 25 pair of ribbon spools rotatable thereby all shiftable with the carriage, a pair of rock arms on said shaft, a pair of operating links connecting said rock arms with said spool rotating devices, a pair of tappets carried by 30 said rock arms, and feed-reversing means shiftable with the carriage and operable by said tappets alternately upon exhaustion of a ribbon from first one spool and then the other. 35

In testimony whereof we hereunto affix our signatures.

HENRY ALLEN AVERY.

OTTO PETERMANN.

EDWIN L. HARMON.
